Primary Examiner—Dominic Simone(74) Attorney, Agent, or Firm—Marshall A. Lerner, Esq.; Finn T. Simmensen, Esq.; Kleinberg & Lerner, LLP(57) CLAIM

The ornamental design for a portion of shoe upper, as shown and described.

DESCRIPTION

FIG. 1 is a perspective view of the portion of shoe upper showing my new design;

FIG. 2 is a right side elevational view thereof;

FIG. 3 is a top plan view thereof;

FIG. 4 is a left side elevational view thereof; and,

FIG. 5 is a front elevational view thereof.

The broken lines showing the bottom in FIG. 1 is for illustrative purposes only and form no part of the claimed design.
